CALK ATTACHMENT FOR BOOTS.

Application filed December 5, 1925. Serial No. 73,470.

Our invention relates to improvements in calk attachments for boots, the objects of which are to provide means whereby rubber boots such as are worn in the woods may be prevented from slipping and may be rendered safe for loggers and woodsmen generally, also to provide means which may be readily attached to or removed from boots of any kind, thus forming a very convenient attachment for the use of persons who may have occasion to go into places where calked boots would be desirable.

5

The invention consists of a pair of calked metal strips pivotally connected together in 15 the manner of a pair of tongues, such strips being provided with clips adapted to grip the sole of a boot and means for securing the outer ends of the strips to the boot heels.

Fig. 1 is a side view of the invention attached to a rubber boot.

Fig. 2 is a plan view of the attachment taken from the underside.

In the drawings like characters of reference indicate corresponding parts in each 25 figure.

The numeral 1 indicates a boot having a welted sole 2, an arch 3 and a heel 4. The numeral 5 indicates a pair of curvilinear strips of metal which are inturned at their forward ends and pivotally connected together as at 6 in the form of a pair of tongues. Intermediate their length, the strips 5 are upwardly curved to conform substantially to the arch 3 as at 7, the outer 35 ends of the strips are then bent downwardly and longitudinally under the heel 4 to form heel portions 8. The numeral 9 indicates a plurality of clips which may be formed integrally with the strips or connected thereto by rivets 10, so as to permit the clips, which are adapted to embrace the welt of the sole 2 to adjust themselves to its curvature.

The heel portions 8 of the strips are apertured as at 11 for the purpose of receiving screws 12 by which the rear end of the attachment is secured to the heel 4 of the boot.

The numeral 13 indicates a plurality of calks riveted at intervals along the strips 50 and projecting downwards therefrom.

Having thus described the several parts of our invention we will now briefly explain its attachment.

The heel portions 8 of the attachment are spread apart and the boot placed in position 55 thereon, the heel portions are then brought together whilst adjusting the strips longitudinally to bring all the clips 9 into suitable gripping engagement with the welt of the sole 2. When a suitable position is attained the heel portions 8 are secured to the heel 4 of the boot 1, which portions, being prevented from outwardly opposed movement, cause a constant and effective grip to be maintained by the clips 9 upon the welted 60 sole.

It will thus be seen that we have invented an attachment which can be conveniently carried by persons having temporary need of non-slipping protection upon their boots, 70 and which can be readily applied, and a means of affording such protection to rubber boots having soles which are incapable of supporting calks in the same manner as leather boots.

75 What we claim as our invention is:

A calk attachment for boots comprising relatively adjustable calk carrying members presenting sole engaging portions curved longitudinally for a portion of their length to conform to the bottom contour of the boot sole, the remaining portion of the length of each member being bent twice at right angles to provide a vertical portion adapted to engage the breast of the heel and 80 a horizontal portion adapted to flatly engage the bottom portion of the heel, said members being equipped with means for gripping the same to the sole of the boot when the members are adjusted to predetermined positions 85 and being adapted to be secured in such adjusted positions by fastening devices passed into the heel of the boot through the horizontal heel engaging portions of the members.

90 Dated at Wistaria, B. C., this 21st day of November 1925.
